UNITED STATES PATENT OFFICE.

CHARLES A. ROLFE, OF CHICAGO, ILLINOIS, ASSIGNOR TO THE ROLFE ELECTRIC COMPANY, OF CHICAGO, ILLINOIS, A CORPORATION OF ILLINOIS.

ELECTRIC-CIRCUIT PROTECTOR.

SPECIFICATION forming part of Letters Patent No. 697,219, dated April 8, 1902.

Application filed December 8, 1900. Serial No. 38,438. (No model.)

To all whom it may concern:

Be it known that I, CHARLES A. ROLFE, a citizen of the United States, residing at Chicago, in the county of Cook and State of Illinois, have invented a certain new and useful Improvement in Electric-Circuit Protectors, (Case No. 7,) of which the following is a full, clear, concise, and exact description, reference being had to the accompanying drawings, forming a part of this specification.

My invention relates to protectors for protecting low-tension instruments and circuits from injury by the intrusion of unduly strong currents, such as power and lighting currents.

The invention relates in particular to a variety of such electrical protectors in which is employed a body or mass of material which may be said to be "softenable" or "fusible"—that is to say, sufficiently responsive or susceptible to a moderate degree of heat to cause it to be softened or fused by the application of such an amount of heat. In certain forms of this style of protector the fusible or softenable material consists of wax. In others it consists of solder. Various kinds of wax have been employed, as have also various kinds of solder, the composition of each being sufficiently varied to cause them to be properly responsive to heat of any desired moderate degree and enduring for any desired moderate length of time. In these protectors the operation of the device is permitted by the fusing or softening of the mass or body of fusible or softenable material, and to such end the devices are each provided with a device for concentrating heat, so that it shall be applied to the said mass or body of material, and also with a circuit-controlling device or set of devices by which the circuit is controlled in any desired way by the fusion or softening of said body of material.

The heat-concentrating devices and the circuit-controlling devices have varied very largely in different forms of protectors. In most instances the heat-concentrating device has consisted of a coil of fine wire, which would become heated and so form a heated mass or ball upon the passage of an unduly strong current through the wire. This coil of fine wire has been so associated with the mass or body of fusible or softenable material

that when the coil has become heated by the unduly strong current the body or mass of fusible or softenable material has been fused or softened. In certain of such devices the heat-concentrating coil has been embedded within the mass or body of material, while in others the coil has been arranged outside of or surrounding the said mass or body. In either case, however, the association has been so close that the generation of a moderate degree of heat in the coil has affected the mass or body of fusible or softening material.

The circuit-controlling devices have usually consisted of suitable mechanisms by which the circuit is opened upon the softening or fusing of the fusible or softenable material, although in certain instances these circuit-controlling devices have been such as to cause the circuit to be shunted to ground instead of being opened. In either case the arrangement is such that when an unduly strong current traverses the heat-concentrating device and causes the generation of a sufficient amount of heat to affect the mass or body of fusible or softenable material the circuit-controlling device operates. In the one case the circuit is opened, and in the other case it is shunted to ground. In both cases the instrument on the circuit and the circuit itself are protected from the unduly strong current, in the first instance by the complete stoppage of the current and in the second by its diversion from the circuit and instrument under protection to another circuit. As an example of a protector of the class mentioned I might cite that described, illustrated, and claimed in the patent to Albert Barrett, No. 445,217, of January 27, 1891, for a thermal cut-out. In this patent the heat-susceptible device consists of a ball or button of wax, and the heat-concentrating mass consists of a coil of wire which is embedded within the material of the wax. The coil of wire surrounds the end of a loop or shank, and a spring is arranged and held under tension by this loop or shank. The ball or button of wax is held against the operation of the spring by a suitable support or abutment. The operation of the device then is that when an unduly strong current intrudes upon the line the coil of wire generates sufficient heat to cause the portion of the wax

ball or button immediately surrounding it to soften. The spring is thereby released and operates so as to withdraw the end of the loop, with the coil surrounding it, from the 5 interior of the ball or button of wax. By such withdrawal and by the continued movement of the coil and loop as they are acted upon by the spring the ends of the coil are ruptured, so as to break or open the circuit.

10 The invention of the present application relates in particular to a releasing device for releasing the spring-actuator embodying in its construction both the heat-concentrating device and the heat-susceptible body or mass.

15 The principal objects of the present invention are to provide an exceedingly simple form of responsive device of this kind, to reduce the cost of manufacture of the same, to arrange for its easy and ready embodiment 20 in the protector and its replacement therein, and to dispense with all connecting-wires.

In this application, for the purpose of illustrating my present invention, I have shown and described a form of protector similar in 25 general arrangement to a protector described, illustrated, and claimed in my application for Letters Patent No. 19,294, filed June 6, 1900. The responsive device of my present invention as embodied in the general form of protector of my said other application forms an exceedingly desirable and advantageous protective device; but I wish it distinctly understood that I consider it possible to embody the said improved responsive device of the 30 35 present application in many and various forms of protective devices, and hence I do not wish to be considered as limiting myself to its embodiment in the particular form of protector which is herein shown and described.

In the accompanying drawings, Figure 1 is a side elevation of a protector embodying my present invention, the said protector being in general arrangement similar to that of my 45 said other application, Serial No. 19,294. Fig. 2 is an end elevation of the same. Fig. 3 is a bottom view of one of the removable holders or circuit-breaking devices of said protector. Fig. 4 is a vertical section through 50 the releasing device employed in said holder. Figs. 5 and 6 are views, the former in side elevation and the latter in vertical section, of certain of the parts going to make up the construction of this releasing device.

55 The form of protector shown is intended for the protection of both sides of an electric circuit, and to such end it is provided with two devices A A, one for each side of the circuit. These devices are mounted upon a suitable 60 base B, which is understood to be composed of insulating material—such, for example, as porcelain or slate. The base B is provided with simple forms of contact-jaws 11, which are arranged to receive metallic shanks 22, provided upon the devices A A. In this way each device A is bodily removable from the

protector by being elevated, so as to withdraw the shanks 22 from the contacts 11.

Each of the devices A consists of a flat insulating-strip 3, preferably composed of fiber, 70 to the opposite ends of which the shanks 22 are secured. The strip 3 is provided with a spring 4, which is secured to one end of the strip and has its spring-arm extended lengthwise over or above the strip. The spring 4 75 is electrically connected with the shank 2 at the end at which the spring is secured. The strip 3 is provided with an aperture, and a releasing device C is arranged to fit into the aperture in the strip 3 and to engage the free 80 end of the spring 4. The releasing device C consists of a hook 5, provided with a coil of fine wire 6, a mass 7, of fusible material, preferably wax, which is associated with the coil of fine wire 6, so as to be responsive to the 85 heat generated in that wire, a simple and desirable way being to embed the coil 6 in the mass 7, and a metallic shell or casing 8, which incloses the associated coil and mass and also the end of the hook 5. One end of the coil 6 90 is connected with the hook 5, as by being soldered to the lower end thereof, as shown in Figs. 4 and 5, while the other end of the coil is connected to the shell 8, as by being soldered to the outside of that shell, as shown 95 in Fig. 4. In this way both the hook 5 and the shell 8 are electrically connected with the coil 6. The shell 8 is desirably made conical in shape, as shown, with the hook 5 extending from its smaller end, so that it can 100 be partly introduced into the aperture in the holder or support 3 and at the same time will engage the rim of the aperture, so as to prevent the shell from passing completely through such aperture. The holder or support 3 is provided with a metallic clip or contact 9, which has one of its ends secured to one of the shanks 2 and extends lengthwise of the holder 3 from said shank along the under side of the said support. The other end 105 of this clip 9 is conveniently cut into a V shape, and the edges of the V are arranged to substantially coincide with portions of the rim of the aperture in the support 3. In this way when the releasing device C is put in position in the device A, so that the hook 5 extends upwardly, and the shell 8 is fitted into and through the aperture of the support 3 the shell will come into contact with the flaring ends of the clip 9, and thus serve to connect one end of the coil with one of the metallic contacts or shanks 2. The spring 4 being connected with the other shank or contact 2, the other end of the heat-coil is connected with this other contact 2.

115 A simple way of arranging the metallic clip 9 and the contact 2, connected therewith, is to stamp out of a piece of metal a single structure, which will comprise the clip 9, a shank 2, and portions 10 and 11, Fig. 2, which will 120 lie above and below the strip 3. This structure can then be secured to the strip 3 by 125

rivets. In the same way a structure can be stamped for the other end of the device A, the said structure consisting of a shank 2, under and over lying portions 10 and 11, the latter of which is slightly bent, so as to form a recess for the lower portion of the loop of the spring. This structure can likewise be riveted to the strip 3.

The operation of the device is as follows:

- 10 Upon the intrusion of an unduly strong current upon the line the coil of wire 6 becomes heated to such an extent as to melt or soften the portion of the fusible mass or body 7 immediately surrounding the coil. This reduces 15 the hold which the fusible or softenable mass 7 has upon the hook 5 to such an extent as to allow the spring 4 to operate and forcibly withdraw the hook 5 from the interior of the mass 7. Upon this taking place the connection 20 of the coil 6 with the shell 8 is ruptured or broken, thereby disconnecting the hook 5 from the shell 8 and opening the circuit. The general arrangement of the protector illustrated and described is shown and described in 25 my said other application, Serial No. 19,294—that is to say, in that application there is shown a support or holder having one of its ends provided with a spring and a releasing device so disposed as to hold the spring normally 30 under tension and to draw against the support or holder, so that the latter acts both as an abutment for the releasing device and also as a holder or support for the spring.

The particular novelty of my present application lies in the construction of the releasing device C and the manner in which this new releasing device is connected with the terminals 22 of the holder 3. This novel form of releasing device can, as I have said, be employed in various forms or styles of protectors other than that herein shown and described. It has many advantages, among which may be mentioned the following: In the first place, it is simple and inexpensive, being composed of a minimum number of elements arranged and connected together in a simple and expeditious manner. In the next place, it dispenses with all connecting-wires, the connections being made directly with the hook 5 and the shell 8, which may be termed the "engaging" members of the releasing device. Again, the arrangement of the releasing device in the protector is very convenient, so that it can be mounted in the protector, 45 when the same is constructed, in a minimum amount of time and can also be replaced with equal facility. Finally, the use of all binding-screws in the circuit-breaking devices or holders is dispensed with, the connections being 50 such that rivets can be employed.

What I claim as my invention is—

1. In a protector for electric circuits, a releasing device comprising a metallic shell, a mass of fusible or softenable material inclosed 65 within the shell, a heat-generating device associated with the softenable or fusible ma-

terial so that the latter will be fused or softened by the generation of heat in the heat-generating device, and a loop or hook engaged by the fusible or softenable mass so as to be held thereby when such mass is hard and to be released when the same is fused or softened, the metallic shell and loop or hook being electrically connected with the heat-generating device.

2. In a protector for electric circuits, a releasing device comprising a metallic shell, a body or mass of fusible or softenable material inclosed within the shell, a coil of fine wire associated with the body or mass of fusible or softenable material so that the latter will be fused or softened by the generation of heat in the coil of wire, and a loop or hook engaged by the fusible or softenable material so as to be held thereby when such material is hard and to be released by the fusion or softening of the same, the said hook having its free end projecting out of the metallic shell and the coil of wire having one of its ends connected with the metallic shell and the other with the loop or hook, substantially as described.

3. In a protector for electric circuits, a releasing device comprising a conical-shaped metallic shell, a body or mass of fusible material inclosed within the shell, a coil of fine wire embedded in the body or mass of fusible material, and a hook having one of its ends surrounded by the coil of fine wire and the other end projected out of the said mass of material and also out of the metallic shell, the coil of wire having one of its ends connected with the hook and the other with the metallic shell, substantially as described.

4. In a protector for electric circuits, a releasing device comprising a conical-shaped metallic shell, a body or mass of wax inclosed within the shell, a coil of fine wire embedded in the body or mass of wax, and a hook having one of its ends surrounded by the coil of fine wire and the other end projected out of the said mass of wax and also out of the metallic shell, the coil of wire having one of its ends connected with the hook and the other with the metallic shell, substantially as described.

5. In a protector for electric circuits, the combination with a releasing device comprising a metallic shell, a body of fusible or softenable material contained by the shell, a heat-generating device associated with the body of fusible or softenable material, and a loop or hook having one of its ends engaged by the said mass of material so as to be held thereby when said material is hard and to be released when the same is fused or softened, the heat-generating device being electrically connected with the shell and hook, of a contact adapted to engage the said metallic shell, and a tension device adapted to engage the hook, substantially as described.

6. In an electrical protector for electric cir-

cuits, the combination with a base having contact-jaws, of a holder consisting of an insulating-strip having its opposite ends provided with contacts adapted to fit into said 5 contact-jaws, said strip being also provided with an aperture between its ends, a spring secured to one end of the strip and connected with the contact at that end, a metallic strip connected with the contact at the other end 10 of the insulating-strip and extended to the aperture therein and constructed with portions arranged to substantially coincide with said aperture, a releasing device comprising a conical shell, a metallic hook, a mass or 15 body of fusible or softenable material, and a coil of fine wire, the said wire being coiled about the end of the hook and connected with the same and with the shell, and the mass of fusible or softenable material being inclosed 20 within the shell and embedding the end of the hook and the fine-wire coil, the said releasing device being arranged with the metallic shell in the aperture in the insulating-strip and in contact with the said contact-strip extending 25 from one of the contacts and the hook in engagement with the spring, substantially as described.

7. In a protector for electric circuits, a holder comprising an insulating-strip having 30 its opposite ends provided with metallic contacts and provided with an aperture between its ends, a metallic strip extended from one of said contact-strips along the under side of the insulating-strip and having a forked end, 35 whose bifurcations embrace the aperture in the insulating-strip, and a spring secured to the other end of the insulating-strip and con-

nected with the contact at such other end, substantially as set forth.

8. In a protector for electric circuits, the 40 combination with a spring and a contact, both composed of conducting material, of a releasing device comprising a metallic shell or casing, a mass of heat-responsive material inclosed therein, a heat-generating device, and 45 a metallic hook or like connection engaged by the heat-responsive material, the said device consisting of a single bodily-removable unitary structure, and the shell or casing and hook being connected in circuit and adapted 50 for engagement with the contact and spring, respectively, substantially as described.

9. In a protector for electric circuits, the combination with a base having contact-jaws, a holder having metallic tips adapted to fit 55 into said contact-jaws and also provided with an aperture, a metallic strip extending from one of said metallic clips to the aperture on the lower side of the holder, a spring mounted at the opposite end of the holder, an excess-current-operated device having a metallic shell adapted to fit into said aperture and also adapted to rest against the said metallic strip, and a connection between said excess-current-operated device and spring for holding the latter normally in tension, substantially 60 as described.

In witness whereof I hereunto subscribe my name this 28th day of November, A. D. 1900.

CHARLES A. ROLFE.
